UNITED STATES PATENT OFFICE.

LAWRENCE V. FRALEY, OF CHICAGO, ILLINOIS, ASSIGNOR, BY MESNE ASSIGNMENTS, TO STANDARD CONVEYOR COMPANY, OF NORTH ST. PAUL, MINNESOTA, A CORPORATION OF MINNESOTA.

PORTABLE CONVEYER.

Application filed February 20, 1920. Serial No. 360,112.

To all whom it may concern:

Be it known that I, LAWRENCE V. FRALEY, a citizen of the United States, residing at Chicago, in the county of Cook and State 5 of Illinois, have invented a certain new and useful Improvement in Portable Conveyers, of which the following is a full, concise, clear, and exact description, reference being had to the accompanying drawings, 10 forming a part of this specification.

This invention relates to portable conveyers.

Conveyers of this type are found particularly useful in transferring loose materials 15 such as dirt, gravel, stone and the like over comparatively short distances, that is, from one pipe to an adjacent pipe or into a bin or other conveyer. They usually include a suitable conveying medium carried by an 20 elongated frame supported upon wheels so that the conveyer may be readily moved about and to the position desired.

The general aim of the present invention is to improve the construction and operation 25 of conveyers of this type.

More specifically one object of this invention is to so construct the receiving end of the conveyer that it may be inserted into or placed in a most advantageous position 30 with respect to the pile of material to be moved.

Another object is to so construct the receiving end of the conveyer frame that it will not jab into the ground and thus interfere with the ready movement of the 35 conveyer from place to place.

Another object is to provide an improved conveyer of such construction as to be proof against loss of material due to leakage or 40 otherwise during the passage of the material therethrough.

Another object is to provide an adjustable support for the conveyer whereby the elevation thereof may be varied at will.

Another object is to provide an improved means for adjustably supporting the drum over which the conveyer apron passes.

Another object is to provide an improved oiling system for the drum.

Other objects and advantages will hereinafter appear.

Two embodiments of the invention are

illustrated in the accompanying drawings.

The views of the drawings are as follows:

Figure 1 is a view in side elevation of a portable conveyer embodying the features of the present invention.

Figure 2 is a section, on a somewhat larger scale, taken on the line 2—2 of 60 Figure 1.

Figure 3 is a horizontal section taken on the line 3—3 of Figure 2.

Figure 4 is a vertical section taken on the line 4—4 of Figure 3.

Figure 5 is a fragmentary, vertical longitudinal section thru the receiving end of the conveyer, taken on the line 5—5 of Figure 6.

Figure 6 is a section taken on the line 6—6 of Figure 5.

Figure 7 is a fragmentary longitudinal section thru one of the conveyer drums or rollers and illustrating a novel form of adjustable support therefor.

Figure 8 is a vertical section taken on the line 8—8 of Figure 7.

Figure 9 is a transverse section through the drum shaft.

Figure 10 is an enlarged sectional view 80 taken on the line 10—10 of Figure 1.

Figure 11, is a fragmentary, vertical, longitudinal section through a portion of the conveyer.

Figure 12 is a sectional view taken on the line 12—12 of Figure 1.

Figure 13 is a fragmentary view in side elevation of the delivery end of the conveyer.

Figure 14 is an isometric view of a part 90 of the receiving end of the conveyer.

Figure 15 is the side elevation of parts of a conveyer frame, shown as an alternative embodiment of my invention;

Figure 16 is a longitudinal sectional view 95 of the nose or receiving end of the conveyer;

Figure 17 is a transverse section through the conveyer frame, taken on line 17—17 of Figure 15 and looking in the direction 100 of the arrows;

Figure 18 is a detailed view of a spring clip employed to maintain resiliently a roller spindle in position;

Figure 19 is a section taken on line 19—19 of Figure 18 and looking in the direction of the arrows;

Figure 20 is a section taken on line 20—20 of Figure 15;

Figure 21 is a section taken on line 21—21 of Figure 15; and

Figure 22 is a section taken on line 22—22 of Figure 15.

- 10 The conveyer includes a long rigid frame preferably of open construction to conserve weight and having a defined channel from end to end through which the material conveyed may pass. The bottom of the channel is closed by the conveying medium in such manner as to be proof against leakage.
- 15 The frame may be constructed in various ways. In the present instance however, the frame includes upper and lower longitudinal sills 10 and 11, respectively, preferably in the form of angle irons as shown (Figures 1, 2, 10 and 11). The upper and lower sills on each side are rigidly connected at intervals by a series of oppositely disposed 20 upright brackets 12. Each bracket is preferably provided with upper and lower lateral ears 13 and 14 secured to the upper and lower sills, respectively, in any appropriate manner, such as by rivets 15. Transverse members 16 preferably in the form of angle irons are riveted or otherwise rigidly secured to the inwardly directed webs 17 preferably cast integral with the brackets. Each bracket is further provided with a bearing portion 18 adapted to receive an end of a spindle 19 rotatably supporting an antifriction roller 20. The brackets extend upwardly and inwardly above the upper sills 10 and terminate in flat faces 21 which together 25 form a convenient means for supporting the longitudinally extending guide plates 22 in an upright position. These plates extend substantially the full length of the conveyer frame and form the side walls of the channel through which the material passes.

The conveying medium forms the bottom of the channel and preferably comprises an endless belt or apron 23 having transverse cleats or flights 24 for obtaining a better grip on the material conveyed. The apron passes over the rollers 20 and along and beneath the lower edges of the guide plates 22. The apron is preferably of such width 30 as to extend somewhat beyond the guide plates 22 in such manner that the plates maintain the material well within the longitudinal edges of the apron. By this construction it will be seen that any possibility of the material leaving the belt is effectively prevented. In order to insure that the apron is maintained sufficiently close to the plates 22, additional rollers 25 may be provided. These rollers are rotatably mounted on 35 spindles 25' supported upon bracket plates

26 riveted or otherwise secured to the upper sills 10. The lower run of the apron may be supported by one or more rollers 28. In the present instance only one of such rollers is employed. This roller is journaled on a 70 suitable spindle 29 supported by means of bracket plates 30 secured to the lower sill 11 and is preferably reduced intermediate its ends to permit the free passage of the flight 24 thereover. The forward or receiving end of the conveyer frame is preferably bevelled off as shown to form a substantially horizontal base portion 31 and a pointed nose 32. The nose is preferably in the form of a casting having an inclined lip 33 and upstanding forwardly tapering shoulders 34 together forming an outwardly flaring mouth for receiving the material to be conveyed. The casting is held in position between side plates 35 by means of connecting rods 36 passing therethrough. The side plates 35 extend from the top to the bottom of the conveyer frame and a short distance back from the extreme end thereof and are firmly secured to the upper and 80 lower sills 10 and 11.

A trough shaped member 36^a is preferably suspended between the side plates 35 and above the conveyer apron to insure proper delivery of the material to the apron. For 95 this purpose this member is positioned in alignment with the receiving mouth of the conveyer frame and with the channel defined by the guide plates 22 and preferably overlaps the inner end of the casting 32 as 100 well as the guide plates 22. This member is held in fixed position by any appropriate means such as angle irons 37 connecting the longitudinal flanges 38 thereof with the side plates 35. A plate 39 secured to and bridging the space between the upper sills 10 extends beneath the conveyer apron at the point where the apron receives the material to catch any of the material that might fall 105 from the belt during the loading thereof. 110

The horizontal portion 31 of the conveyer is preferably closed by a plate 40 removably secured to the lower sills 11 by any convenient means such as bolts 41. The forward edge of the plate is seated in a suitable transverse groove 42 formed in the casting 32, the plate extending rearwardly therefrom substantially the length of the side plates 35. 115

Thus it will be seen that the receiving end of the conveyer frame is completely closed and that the under face thereof is free from sharp corners which might jab into the ground and thus interfere with the ready movement of the conveyer from place to place. 120

The lower drum or pulley 43 for the conveyer apron is mounted within this closed end of the frame in a novel manner as will be explained.

This drum is preferably hollow and is pro- 125

vided at each end with a bearing in the form of a bushing 44. The drum is rotatably mounted upon a horizontal shaft 45 extending through suitable elongated openings 46 in the side plates 35. Each end of the shaft 5 is firmly clamped in position between a pair of diametrically disposed screws 47 which are threaded through a collar 48 and project into suitably fashioned recesses 49 in a sleeve 10 50 secured to each end of the shaft. Each collar 48 is secured to a side plate 35 by means of bolts 51 or the like so as to surround the opening 46 therethrough. The screws 47 are preferably arranged lengthwise 15 of the conveyer and thus form a convenient means for obtaining a proper adjustment of the drum shaft 45 with respect to the conveyer belt. Jam nuts 51' may be employed to lock the screws in any position 20 of adjustment. A cover or cap 52 removably secured to the collar 48 by any convenient means such as bolts 53 forms a tight housing for each end of the shaft.

Various methods may be employed for 25 lubricating the drum shaft. In the present instance however the shaft is provided at each end with a main duct 54 substantially axial of the shaft and transverse ducts 55 leading from the main duct to the periphery 30 of the shaft. The entrance to the main duct 54 is preferably normally closed by a removable plug 56. After removing the cap 52, the plug 56 may be removed and a suitable lubricant forced through the ducts to the interior 35 of the drum and to the periphery of the shaft. The plug 56 and cap 52 may then be replaced in their closing positions. By this construction sufficient lubricant may be supplied at any one time to give proper 40 lubrication for a considerable period. In order to exclude dust and dirt and to prevent leakage of the lubricant a ring 57 of suitable packing material may be inserted between the drum and sleeve 50.

45 Referring now to the upper or delivery end of the conveyer frame it will be noted (Figures 12 and 13) that the opposite sides thereof are closed by means of side plates 58. These plates extend from top to bottom of 50 the frame and are riveted or otherwise secured to the lower sills 11 and also to the ends of the upper sills 10. Upright stiffening members preferably in the form of angle irons 59 and 60 are secured to each of these 55 plates.

The upper drum 61 of the conveyer apron is secured to a horizontal shaft 62 extending crosswise of the frame and through suitable slots 63 in the side plates 58. Each 60 end of this shaft is journaled in a slideblock 64 mounted for lengthwise sliding movement between suitable guides 65 carried by the side plates. An adjusting screw 66 connected with each slideblock 64 passes through 65 a flange of the angle iron 60 and is provided

with nuts 67 for securing the screw in any position of adjustment. By this construction the drum 61 may be adjusted lengthwise of the frame to effect any desired tension in the conveyer apron.

70

As previously pointed out the conveyer frame is mounted upon a wheeled support of any approved construction whereby the conveyer may be readily moved about from placed to place. In the present instance this support is made up of steel tubing and comprises rigidly connected longitudinal members 68 and upright members 69 preferably connected by a transverse member 70 and a cross head 71. The free ends of the longitudinal and upright members are secured to the conveyer frame by any convenient means such as bracket plates 72-73, respectively, preferably riveted to the upper 75 and lower sills 10 and 11.

80

The upright members 69 are mounted for vertical sliding movement in sleeves 74. Each sleeve 74 is preferably formed as an integral part of a bracket 75 secured to an axle 76 carried by the supporting wheels 77.

90

Various means may be provided for maintaining the upright members 69 in any position of adjustment in the sleeves 74. In the present instance this means includes a screw shaft 78 fixed at its upper end in the cross head 71 and extending through an internally threaded worm gear 79 seated upon a transverse member 80 connecting the brackets 75. As shown in Figures 3 and 4, the transverse member 80 is formed with an opening 81 to permit lengthwise movement of the screw shaft 78 therethrough. The worm gear 79 is actuated by a worm 82 fixed to a horizontal shaft 83 journaled in suitable bearings 84 and 85 carried by the member 80. Shaft 83 may be provided with a pin 86 or otherwise fashioned to receive a suitable tool, such for instance as is shown in dotted lines in Figure 2, for rotating the shaft. Upon the rotation of shaft 83 and its worm 82, worm gear 79 is rotated with respect to the screw shaft 78 thus effecting a raising or lowering of the screw shaft, and a consequent vertical adjustment of the conveyer frame to any desired elevation.

100

110 The conveyer may be provided with any appropriate form of power unit for actuating the conveyer apron. In the present instance this unit comprises an internal combustion engine 87 of any approved type. As shown in Figure 1 the engine is mounted upon a pair of angle irons 88 secured to the longitudinal members 68. A sprocket wheel 89 secured to the crank shaft 90 is operatively connected with a sprocket 91 by means of a chain 92. Sprocket 91 is keyed to a shaft 93 which also carries a sprocket 94 operatively connected with a sprocket 95 by means of a chain 96. The sprocket 95 is keyed 120 or otherwise secured to the upper drum shaft 125 130

62 to rotate therewith. Thus when the engine 87 is set in motion the drum shaft 62 is actuated through the gearing just described and a consequent rotation is imparted to the upper drum 61. Rotation of the upper drum effects a continuous travel of the endless belt or apron 23, in a well known manner.

10 The operation of the device may now be briefly described. Assuming that it is desired to transfer a pile of loose material into a truck or other conveyance, the conveyer is moved to position with its receiving end inserted into the pile or in a most advantageous 15 position with respect to the pile, and with its delivery end over the truck. By rotating the worm shaft 83 the conveyer frame may be raised or lowered to position the delivery end thereof at a proper elevation above the 20 truck. The engine 87 may then be set in motion and the material shoveled or raked over or through the receiving mouth and onto the receiving end of the conveyer apron. The material is then advanced by the traveling 25 apron through the channel defined by the guide plates 22 up to and over the upper drum 61 from which point it drops by gravity into the truck. It is obvious that the conveyer may be employed in a similar manner to transfer materials from one pile to another or into a bin or other conveyer.

30 The tapered end of the conveyer frame permits the same to be actually inserted in the pile of material or to rest squarely upon the ground at the foot of the pile. In either 35 position it is not necessary to lift the material to any great extent in loading the same onto the conveyer. Furthermore by so shaping the receiving end of the conveyer frame there are no sharp corners which might jab into the ground and thus interfere with the ready movement of the conveyer from place to place.

40 A modified form of conveyer frame construction is illustrated in Figures 15 to 22, inclusive. As in the conveyer hereinabove described this frame includes upper and lower longitudinal sills 10¹ and 11¹, respectively, preferably in the form of angle irons 45 extending substantially from one end to the other of the frame. The upper and lower sills on each side are rigidly connected at intervals by a series of oppositely disposed upright brackets 12¹ secured at their upper 50 and lower ends to the vertical flanges of the upper and lower sills, respectively. Transverse members 16¹ preferably in the form of angle irons are riveted or otherwise rigidly secured to the inwardly directed webs 17¹ preferably cast integral with the brackets.

55 As shown particularly in Figures 17, 20, 21 and 22 the horizontal flanges of the upper sills 10¹ extend inwardly and serve as supports for longitudinally extending an-

gle bars 97 positioned along the inner edges thereof. Longitudinal guide plates 22' are riveted or otherwise secured to the angle bars 97. These plates extend substantially the full length of the conveyer frame and 70 form the side walls of the channel through which the material passes.

75 The endless belt or conveyer apron 23' forms the bottom of the conveyer channel. The apron is threaded over a drum 43' similar to that hereinabove described at the receiving end of the frame and over a second drum (not shown) at the delivery end of the frame, and is actuated preferably by means such as before described. The upper run of 80 the apron passes over the rollers 20' and beneath the lower edges of the guide plates 22'. The apron is preferably of such width as to extend somewhat beyond the guide plates 22' in such manner that the plates 85 maintain the material well within the longitudinal edges of the apron.

90 The rollers 20' are rotatably mounted upon suitable spindles 98 extending through the vertical flanges of longitudinal angle bars 99. Bars 99 are preferably supported by suitable angle brackets 100 secured thereto and to the transverse member 16'. The bars 99 are preferably so positioned that the horizontal flanges thereof engage beneath and support the free longitudinal edges of the conveyer apron 23' (see Figures 21 and 22).

95 The forward or receiving end of the frame is similar to the receiving end of the frame hereinabove described in that it is completely enclosed and the bottom portion thereof is bevelled off to form a pointed nose as shown in Figures 15 and 16. The nose is 100 preferably in the form of a casting having any inclined lip 33' terminating in an acute rounded forward edge 32' adapted to be wedged into the pile of material to be conveyed. The casting is held in position between side plates 35' by means of connecting rods 36' passing therethrough. The side plates 35' are riveted or otherwise secured to the upper and lower sills 10' and 11' and extend some distance back from the extreme 105 forward tip of the conveyer frame. (See Figure 15).

110 The bevelled bottom portion of the frame is closed by means of a fixed plate 40' and a hinged plate 101, as indicated in Figures 15, 16 and 20. Plate 101 is suspended at one end from a spindle 102 by means of angle brackets 103. The spindle 102 passes through the brackets 103, side plates 35' and the lower sill members 11' and is held in place by any appropriate means such as cotter pins 104. The plate is normally closed against the bottom flanges of the lower sills 11' and releasably held in this position by means of bolts 105 or the like. Reinforcing strips 106 secured to the plate afford the nec- 115 120 125 130

essary stiffness. When it is desired to gain access to the interior of the conveyer frame it is only necessary to remove the bolts 105 and swing the plate downwardly as indicated by the dotted line position of Figure 16. In order to permit this swinging movement of the plate the side margins thereof to the rear of the pivot point are cut away to provide the necessary clearance.

11 Plate 40' may be secured to the lower sills 11' by rivets or bolts and extends preferably from the rear extremity of the hinged plate 101 to the ends of the side plates 35' (see Figures 15 and 17).

12 The top of the receiving end of the conveyer frame is closed by means of a trough shaped member 36^b, the belt 23', and a belt supporting plate 39', as illustrated in Figure 16. The forward end of the trough member

13 36^b rests within a shallow seat 107 formed upon rear portion of the casting 33'. Member 39' is positioned below the belt 23' with its longitudinal edges extending to the irons 10' and lying upon the brackets 108 to which 14 they are preferably riveted.

15 The belt supporting plate 39' is secured in position by any appropriate means such as angle brackets 108 secured to the side plates 35'. The purpose of the plate 39' is 16 to support the belt 23' at the loading point and thus prevent such a sagging of the belt as might permit the escape of the material from the belt beneath the side plates 22' and into the closed end of the frame.

17 Within the closed or receiving end of the conveyer frame the transverse members 16' are supported by means of angle brackets 108 secured to the side plates 35'. (See Figure 17). The belt supporting rollers 20' 18 are supported upon spindles 98' which are somewhat longer than the spindles 98 previously referred to. Spindles 98' extend through the angle bars 99 and also through one of the side plates 35' to the outside of 19 the conveyer frame. The projecting end of the spindle is bent over as shown at 109 and is held in place by any appropriate means such as a spring clip 110 secured at one end to the side plate 35'. Thus in removing a 20 roller 20' it is only necessary to disengage the end 109 from the clip and withdraw the spindle 98'.

21 It is obvious that a similar clip might be employed to retain the other spindles 98 in place. In the present instance however cotter pins 111 are employed to prevent the removal of the spindles 98.

22 Referring to the rear or delivery end of the conveyer frame it will be seen from Figure 15 that the same is provided with side plates 58' in the form of ribbed castings. A longitudinal slot 63' is provided for slidably receiving a bearing block 64' forming an adjustable support for the shaft 23 62'. The rear or upper conveyer belt drum

(not shown) is preferably keyed to this shaft. Any appropriate means such as an angle iron 59' may be employed to close the open end of the slot 63'.

24 An adjusting screw 66' screwed through 70 an ear 67' and having a rotatable bearing in the block 64' forms a convenient means for adjusting the shaft 62' to effect the desired tension in the conveyer belt.

25 The function and operation of the modified form of the invention last described is substantially the same as the form of the invention first described.

26 Various changes may be made in either of the embodiments of the invention hereinabove specifically described without departing from or sacrificing any of the advantages of the invention defined in the following claims.

27 I claim:—

28 1. In a device of the class described, a frame comprising a pair of upper and a pair of lower longitudinal sills, upright spaced brackets connecting said longitudinal sills at intervals, transverse members connecting said upright spaced brackets, the upper ends of said upright brackets projecting above the upper longitudinal sills, longitudinal guide plates extending along the upper sills and secured to the upper 90 projecting ends of said upright brackets and an endless traveling belt supported within said frame beneath said guide plates.

29 2. In a device of the class described, the combination with a frame and a conveyer 100 apron carried thereby, of a wheeled support for said frame, said wheeled support comprising carrying wheels, an axle for said wheels, sleeve members carried by said axle, upright members secured to the conveyer 105 frame and extending down through said sleeve members for slidable movement therein, a cross head secured to said upright members, a screw fixed at its upper end in said cross head, and means carried by the 110 axle for turning said screw to vary the elevation of the conveyer frame.

30 3. In a device of the class described, the combination with a frame and a conveyer 115 apron carried thereby, of a wheeled support for said frame, said wheeled support comprising carrying wheels, an axle for said wheels, sleeve members carried by said axle, upright members secured to the conveyer 120 frame and extending down through said sleeve members for slidable movement therein, a cross head secured to said upright members, a screw fixed at its upper end in said cross head, and means carried by the axle 125 for turning said screw to vary the elevation of the conveyer frame, said screw turning means comprising a worm gear having threaded engagement on the screw and fixed against longitudinal movement along the screw and a worm meshing with said worm 130

gear to thread the screw upwardly or downwardly through said worm gear.

4. In a device of the class described, a longitudinally inclined conveyer frame, the forward end of said inclined frame terminating in a horizontal portion for cooperation with the ground, a plate hingedly mounted in said horizontal portion and a fixed plate secured to the bottom of the conveyer frame 10 and extending from said hinged plate up along the lower inclined surface of said frame.

5. In a device of the class described, a longitudinally inclined conveyer frame, the forward end of said inclined frame terminating in a horizontal portion for cooperation with the ground, a nose member at the forward end of said horizontal portion, 15

and a plate hingedly mounted in said horizontal portion and closing against said nose 20 member.

6. In a device of the class described, a longitudinally inclined conveyer frame, the forward end of said inclined conveyer frame terminating in a horizontal portion for co- 25 operation with the ground, a nose member at the forward end of said horizontal portion, a plate hingedly mounted in said horizontal portion and closing against said nose member, and means between said plate and said nose member for holding said plate in closed position thereagainst.

In witness whereof I hereunto subscribe my name this 17 day of February, 1920.

LAWRENCE V. FRALEY.
